(57) **CLAIM**

The ornamental design for a support frame rail for supporting a photovoltaic panel on a surface, as shown and described.

DESCRIPTION

FIG. 1 is a front, right perspective view of a support frame rail for supporting a photovoltaic panel on a surface showing our new design;

FIG. 2 is a front, left perspective view thereof;

FIG. 3 is a top plan view thereof;

FIG. 4 is a left side elevation view thereof;

FIG. 5 is a right side elevation view thereof;

FIG. 6 is a bottom plan view thereof;

FIG. 7 is a front, right perspective view of a support frame rail for supporting a photovoltaic panel on a surface in accordance with a second embodiment showing our new design;

FIG. 8 is a front, left perspective view thereof;

FIG. 9 is a top plan view thereof;

FIG. 10 is a left side elevation view thereof;

FIG. 11 is a right side elevation view thereof; and,

FIG. 12 is a bottom plan view thereof.
